AUTOMOBILE EXHAUST SHROUD

Louis A. Koch, Jr., Louisville, Ky.

Application September 8, 1936, Serial No. 99,896

8 Claims. (Cl. 138—25)

My invention pertains to specific structures of automobile exhaust extensions or shrouds.

Since the pipe which conducts the hot exhaust gases from internal combustion engines to the rear of automobiles for expulsion soon becomes rusty and unsightly from being subjected to extreme temperatures and the elements, ornamented exhaust extensions have been evolved to conceal the exposed discharge end of the pipe and to direct the gases with entrained carbon particles so as to prevent marring the exquisite finish of the modern automobile. In the beginning these devices were made of base metals which soon rusted, then enamels and nickel plate were applied and discarded as incompetent. This was followed by chromium plate and stainless steel together with a reflector element, sometimes referred to as a "jewel" or reflex unit. The latter were applied by conventional methods such as a bezel and screw or prongs which entailed perforating the outer surface of the terminus or shell like portion of the shroud for receiving the screw or prongs. These perforations, even though apparently closed by the screw or prongs, provided a passage for the hot gases to the exposed highly finished surface. This resulted in damaging the embellished surfaces and the reflex unit. Therefore the main object of this invention is to provide permanence for the embellishing elements.

A further object lies in providing means to accomplish this desirable result without materially affecting the cost of production and thereby provide the public with an enduring exhaust extension at the same established or popular price.

With the foregoing and other objects, which will be revealed as the description of the details of the structure proceeds and hereinafter claimed, it must be understood that changes from the selected embodiment of my invention can be made without departing from the scope of my invention.

Preferred embodiments of my invention have been illustrated in the accompanying drawing in which—

Figure 1 is a plan view of my automobile exhaust shroud.

Fig. 2 is a side elevation of Fig. 1 shown partially in section.

Fig. 3 is an end elevation of Fig. 1.

Reference numeral 1 indicates a tubular sleeve fashioned to telescopically embrace the end of a conventional exhaust pipe terminating at the rear of an automobile, while 1a represents sub-

stantially parallel juxtaposed tongues extending from said sleeve and perforated to receive bolts b, all of which are organized for secure attachment to said pipe.

Numerical 11 indicates a projecting flared shell-like body of steel, open at the bottom and referred to herein as a "terminus." The primary function of this body is to rearwardly convey and downwardly direct the exhaust gases which frequently reach a temperature of 875° F., while the secondary function is to obscure the rusty exposed surface of the exhaust pipe. Superposed on and spaced from the terminus is a stainless steel covering or veneer indicated by numeral 2 secured thereon by clinched tongues 2a or their equivalent. Between the terminus and veneer is disposed an insulating medium 3 provided to prevent the heat from being transmitted to the veneer, thereby protecting it from discoloration. It has been found that shrouds made of standard chrome nickel stainless steel will yield to the encountered heat by developing a straw color. To make the shroud entirely of stainless steel results in a prohibitive price. The incident invention contemplates using common low priced sheet steel for the portion of the shroud indicated by numerals 1 and 11, superior stainless steel or other highly finished metal for the exposed veneer 2 and then protecting it against discoloration by insulating as adverted to supra. This procedure eliminates the expense of applying chrome or other expensive plating to the entire exhaust extension and substitutes therefor an inexpensive sheet metal stamping which can be of base material having the exposed surface of the veneer highly finished and protected by insulation.

The veneer can be perforated to receive reflex unit J. It will be noted that the jewel is also so located that it will be protected from the heat and gases and that there are no perforations extending through the terminus body which have been found to provide a passage for heat and the exhaust gases.

It will thus be perceived that the objects of this invention as adverted to at the outset can be realized by practicing the teachings disclosed herein.

I claim:

1. An extension for a motor vehicle exhaust pipe comprising a tubular sleeve portion, and remote thereto a terminus to direct exhaust gases from said pipe, the outer surface of said terminus

50

55

being equipped with a veneer which embraces a portion of a reflector body.

2. An extension for a motor vehicle exhaust pipe comprising a tubular sleeve portion, and remote thereto a terminus to direct exhaust gases from said pipe, the outer surface of said terminus being equipped with a veneer and provided with means for insulating said veneer from the heat of said exhaust gases.
- 5 3. An extension for a motor vehicle exhaust pipe comprising a tubular sleeve portion, and remote thereto a terminus to direct exhaust gases from said pipe, the outer surface of said terminus being equipped with a veneer and means for utilizing said veneer to support a reflector body on said terminus.
- 10 4. An extension for a motor vehicle exhaust pipe comprising a tubular sleeve portion, and remote thereto an imperforate terminus to direct 20 exhaust gases from said pipe, the outer surface of said terminus being equipped with a veneer which embraces a portion of a reflector body.
- 15 5. An extension for a motor vehicle exhaust pipe comprising a tubular sleeve portion, and remote thereto a terminus to direct exhaust gases from said pipe, the outer surface of said terminus being equipped with a reflector body and means 25 for insulating said body from the heat of said gases.

6. A tail pipe spout comprising an inner wall structure, an outer wall structure thermally insulated from the inner wall structure, said outer wall structure extending over and concealing the inner wall structure and providing a decorative covering therefor, and means for securing the said structures to a tail pipe in such position that exhaust gases from said pipe will be discharged against said inner wall.

7. A tail pipe spout comprising an inner wall 10 structure, an outer wall structure spaced from the inner wall structure, a solid material of low heat conductivity in the said space, said outer wall structure extending over and concealing the inner wall structure and providing a decorative covering therefor, and means for securing the said structures to a tail pipe in such position that exhaust gases from said pipe will be discharged against said inner wall.

8. A tail pipe spout comprising an inner wall 20 structure adapted to extend beyond the tail pipe and having a cut-away portion to deflect the discharged gases, an outer wall structure thermally insulated from said inner wall structure and extending over and concealing the said inner wall 25 structure to provide a decorative covering therefor, and means for securing the spout to the tail pipe.
